(57) **CLAIM**

The ornamental design for a massage chair, as shown and described.

DESCRIPTION

FIG. 1 is a front elevation view of a massage chair showing my new design;

FIG. 2 is a rear elevation view thereof;

FIG. 3 is a left side view thereof;

FIG. 4 is a right side view thereof;

FIG. 5 is a top plan view thereof;

FIG. 6 is a perspective view thereof; and,

FIG. 7 is a right side view of a massage chair, shown in a second position of use.

The broken lines in the drawings depict portions of the massage chair that form no part of the claimed design.
